UNITED STATES PATENT OFFICE.

OLIVER P. FRITCHLE, OF DENVER, COLORADO.

CONNECTOR FOR ELECTROCHEMICAL APPARATUS.

SPECIFICATION forming part of Letters Patent No. 768,175, dated August 23, 1904.

Application filed December 28, 1903. Serial No. 186,875. (No model.)

To all whom it may concern:

Be it known that I, OLIVER P. FRITCHLE, a citizen of the United States, residing at Denver, in the county of Denver and State of Colorado, have invented certain new and useful Improvements in Connectors for Electrochemical Apparatus, of which the following is a specification.

This connector is especially intended for use with storage batteries, electrolytic cells, and other apparatus requiring an easily-detachable connector which will resist the action of corrosive liquids and fumes.

The connector comprises mercury-cups, preferably of copper plated with nickel, which are secured to the electrodes; a coupler, preferably a heavy copper wire or rod sheathed with lead except at its ends, the ends of the sheath being grooved and formed into bulbs and the ends of the wire being nickel-plated, and soft-rubber sleeves which fit closely upon the mercury-cups and the bulbed ends of the coupler - sheath and have punctured diaphragms to receive the ends of the coupler-wire, but automatically close when the coupler is withdrawn, thereby preventing the escape of mercury.

Referring to the accompanying drawings, Figure 1 is a vertical section through the connector and the upper ends of two electrodes joined thereby; and Fig. 2 is a vertical section through the connector with its several elements detached, but in position to be assembled.

The connector comprises a mercury-cup 1, preferably of copper plated with nickel or some other metal which is insoluble in and non-absorbent of mercury. The cup is secured to the electrode 2 by an integral threaded stem 3. When the connector is used for lead storage batteries, the stem 3 is tinned and cast into a lug 4 at the upper end of the electrode. The mercury-cup has external annular grooves 5 and is partly filled with mercury 6.

The coupler 7 consists of a heavy copper wire or rod 8 covered with a lead sheath 9 except at the ends 10, which are received by the mercury-cups. The lead sheath may be cast on the copper wire, this being previously

tinned. The exposed ends 10 which enter the mercury are plated with nickel. The lead sheath has grooves 11 near its ends and the ends are formed into bulbs 12. The exposed ends 10 of the coupler-wire should be of considerably less diameter than that of the recesses in the mercury-cups and should not extend to the bottom of these cups. This not only prevents the coupler from displacing the mercury from the cups, but allows either electrode to vibrate without transmitting the vibrations to the other electrode, the coupler being supported entirely by the rubber sleeves. The connector is thus especially serviceable for use with automobile-batteries.

Each of the soft-rubber sleeves 13 has a lower central bore 14, which fits closely upon the mercury-cup and usually prevents any electrolyte from creeping up the cup. As a further precaution, an acid-proof grease may be placed in the cup-grooves 5 and around the electrode-lugs 4. Each sleeve also has an upper central bore 15, which receives and fits closely upon the lead bulb 12 of the coupler 7, preventing any accidental dislodgment of the coupler. Between the bores 14 and 15 is an integral diaphragm 16, which is centrally punctured to receive the end 10 of the coupler-wire when forcibly inserted, but to automatically close when the coupler is withdrawn, thereby preventing any escape of mercury from the cup.

This coupler has been found to be entirely proof against the action of the acids and fumes of the ordinary lead storage battery, remains in perfect condition without attention, permits the elements to be easily uncoupled, and avoids the broken connections which occur when the elements are rigidly connected by lead straps fused together.

I claim:

1. An electric connector, comprising a mercury-cup, a coupler having an end which enters said cup, and a carrier of flexible, non-conductive material supporting said coupler with its end within but out of contact with said cup, as set forth.

2. An electric connector, comprising a mercury-cup, a coupler having an end which enters said cup, and a sleeve of flexible, non-con-

ductive material carried by said cup and supporting said coupler with its end within but out of contact with the cup, as set forth.

3. An electric connector, comprising a mercury-cup, a coupler having an end which enters said cup, and a rubber carrier supporting said coupler with its end within but out of contact with said cup, as set forth.

4. An electric connector, comprising a mercury-cup, a coupler having an end which enters said cup, and a rubber sleeve carried by said cup and supporting said coupler with its end within but out of contact with the cup, as set forth.

15 5. An electric connector, comprising an externally-grooved mercury-cup, a coupler having an end which enters said cup, and an elastic sleeve inclosing said cup and coupler end, as set forth.

20 6. An electric connector, comprising a mercury-cup, a coupler having an end which enters said cup and an annular groove near its end, and an elastic sleeve inclosing said cup and coupler end and entering said groove, as set forth.

25 7. An electric connector, comprising a mercury-cup, a coupler having an end which enters said cup and a bulb near its end, and an elastic sleeve inclosing said cup and bulb, as set forth.

30 8. An electric connector, comprising an externally-grooved mercury-cup, a coupler having an end which enters said cup and a bulb near its end, and an elastic sleeve inclosing

35 said cup and bulb, as set forth.

9. An electric connector, comprising a mercury-cup, a coupler having an end which enters said cup, and an elastic member carried by said cup and having a perforated portion

40 to receive said coupler end but close when it is withdrawn, as set forth.

10. An electric connector, comprising a mercury-cup, a coupler having an end which enters said cup, and an elastic sleeve inclosing

45 said cup and coupler end and having a perforated diaphragm which will close when the coupler is withdrawn, as set forth.

11. An electric connector, comprising an externally-grooved mercury-cup, a coupler having an end which enters said cup and a bulb near its end, and an elastic sleeve inclosing said cup and bulb and having a perforated diaphragm to receive said coupler end but close when it is withdrawn, as set forth.

12. An electric connector, comprising a mercury-cup, a coupler having an end which enters said cup and a sheath of non-corrosive metal, and an elastic sleeve inclosing said cup and coupler end, as set forth.

13. An electric connector, comprising a mercury-cup, a coupler having an end which enters said cup and a sheath of non-corrosive metal, said sheath having a bulbed end, and an elastic sleeve inclosing said cup and bulbed end, as set forth.

14. An electric connector, comprising a mercury-cup, a coupler having an end which enters said cup, said coupler consisting of a copper wire having a tinned body portion and a lead sheath cast thereon, and an elastic sleeve inclosing said cup and coupler end, as set forth.

15. An electric connector, comprising a mercury-cup having a stem coated with tin and surrounded by a lug of cast lead, a coupler having an end which enters said cup, said coupler consisting of a copper wire having a tinned body portion and a lead sheath cast thereon, and an elastic sleeve inclosing said cup and coupler end, as set forth.

16. An electric connector, comprising a mercury-cup and a coupler having an end which enters said cup, said cup and coupler end coated with nickel, as set forth.

In testimony whereof I affix my signature in presence of two witnesses.

OLIVER P. FRITCHLE.
